ATTORNEY'S.

UNITED STATES PATENT OFFICE

CALEY A. FOREMAN, OF SCHLATER, MISSISSIPPI

COMBINED REFRIGERATOR AND DISPENSING CABINET

Application filed June 3, 1929. Serial No. 368,022.

This invention relates to a combined refrigerator and dispensing cabinet, and it has for its object to provide a device of this character intended for store use, and having as 5 its primary object to maintain a large number of soft drink bottles in a refrigerated condition, and in such a position that they may be easily inspected, and the desired bottle selected while, at the same time, the waste 10 ice water from the ice used in cooling the bottles is utilized to cool the lower compartment of the cabinet, in which meats, butter, or other articles may be kept in a refrigerated condition and, at the same time, on display.

15 Further objects of the invention will be set forth in the detailed description which follows.

In the accompanying drawing:

Figure 1 is a perspective view of a cabinet 20 constructed in accordance with the invention, and

Figure 2 is a rear view thereof.

Like numerals designate corresponding parts in both of the figures of the drawing. 25 Referring to the drawings, 5 designates a cabinet which, preferably, has an inclined front wall 6, the major portion of which consists of glass panes 7 and 8, through which the contents of the cabinet are rendered visible.

The cabinet is divided by a horizontal partition 9, into an upper compartment 10, and a lower compartment 11. An ice water tank 12 is supported upon the partition 9 and 35 serves to receive bottles 13, the contents of which are to be kept in a chilled condition. The tank 12 is water-tight, and by piling cracked ice on the tops of the bottles, the bottles are maintained in a refrigerated condition. 40 A pipe 14 leads from the bottom of the tank 12 and is connected to a horizontal cooling coil 14^a, which lies flat upon the bottom 15 of the cabinet, and chills the lower compartment 11, and any food stuffs which 45 may be placed in said compartment. The coil terminates in an upstanding bend 16, the discharge leg of which constitutes an overflow pipe 17, which may lead off to any suitable point of drainage.

50 It will be observed that the upstanding

bend 16 lies at such a height that the coil 14^a is kept filled with ice water and that the level of the ice water in the tank is maintained at a point near the top of said tank. The top of the cabinet is provided with a pair of 55 sliding doors 18 and 19, which may be operated independently of each other, said doors complementally occupying substantially the entire top of the cabinet, so that by manipulating one or the other of said doors, substantially the whole area of the tank is uncovered, so that any desired bottle may be selected and removed.

The rear side of the cabinet is provided with doors 20, through which access may be 60 had to the interior of the cabinet, and particularly to the lower compartment 11.

From the foregoing description, it will be seen that very simple and efficient means are herein provided for accomplishing the objects of the invention. However, it is to be understood that the invention is not limited to the precise construction set forth, but that it includes within its purview whatever changes fairly come within either the terms 70 or the spirit of the appended claims.

Having described my invention, what I claim is:

1. A combined refrigerating and display cabinet, comprising a box-like receptacle divided by a partition into upper and lower compartments, doors in the top of the cabinet for access to the upper compartment, additional doors in a side of the cabinet for providing access to the lower compartment, and 80 a tank in the upper compartment substantially co-extensive in length and width with with the receptacle, a drain pipe leading from said tank and including a cooling coil disposed in the lower compartment, and means 85 carried by said pipe for automatically maintaining the level of ice water in the tank, at a point adjacent the top thereof.

2. The combination with a box-like receptacle having a transparent front wall, means 95 for dividing the same into upper and lower compartments, a bottle receiving tank in the upper compartment, doors in the top of the receptacle for rendering all parts of said tank accessible, and an overflow pipe includ-

ing a horizontal coil in its length, said coil being disposed upon the bottom of the lower compartment, said pipe including a trap which extends upwardly to a point adjacent the upper edge of said tank.

- 5 3. A device of the character described, comprising a case, a tank constituting an upper compartment for the case, the space within the case, below said tank, constituting a lower compartment, a drain pipe leading from the bottom of the tank and extended in the form of convolutions along the bottom of the lower compartment, said convolutions terminating in an overflow pipe which comprises an upwardly bent trap, the overflow point of which lies at such height as to maintain the level of water within the tank at a point materially above the bottom thereof, and doors in the case through which ice may be introduced to the tank and bottles may be placed in said tank or removed therefrom.
